FOREIGN PATENT DOCUMENTS

WO WO 2005034699 A1 * 4/2005

* cited by examiner

Primary Examiner—Cathron C. Brooks*Assistant Examiner*—Ricky Pham(74) *Attorney, Agent, or Firm*—Lawrence Cruz; Steven A. Garner(57) **CLAIM**

The ornamental design for a stand mixer, as shown and described.

DESCRIPTION

FIG. 1 is a perspective view of a stand mixer showing our new design;

FIG. 2 is a right side view thereof;

FIG. 3 is a front view thereof;

FIG. 4 is a top view thereof;

FIG. 5 is a left side view thereof;

FIG. 6 is a rear view thereof; and,

FIG. 7 is a bottom view.

The broken lines are shown for illustrative purposes only and form no part of the claimed design.
